UNITED STATES PATENT OFFICE

114,830

DESIGN FOR A CASING FOR DOOR CLOSING
AND CHECKING DEVICE OR SIMILAR
ARTICLE

Louis F. Schmidt, Chicago, Ill., assignor to Norton Lasier Company, Chicago, Ill., a corporation of Illinois

Application March 19, 1938, Serial No. 75,947

Term of patent 7 years

To all whom it may concern:

Be it known that I, Louis F. Schmidt, a citizen of the United States, residing in Chicago, in the county of Cook and State of Illinois, have invented a new, original, and ornamental Design for a Casing for Door Closing and Checking Device or Similar Article, of which the following is a specification, reference being had to the accompanying drawing forming part thereof.

Figure 1 of the drawing is a perspective view of a casing showing my new design; and Figure

2 is a side elevational view of the casing shown in Figure 1.

The top and back of the casing, which are not shown, are plain. The casing as seen from the opposite perspective has the same appearance.

I claim:

The ornamental design for a casing for door closing and checking device or similar article, substantially as shown and described.

LOUIS F. SCHMIDT.
